UNITED STATES PATENT OFFICE.

WILLIAM T. HAMLIN AND CHARLES JOHANN, OF CHICAGO, ILLINOIS.

DESIGN FOR A BROOM AND BRUSH HOLDER.

SPECIFICATION forming part of Design No. 31,123, dated July 4, 1899.

Application filed June 10, 1899. Serial No. 720,090. Term of patent 7 years.

To all whom it may concern:

Be it known that we, WILLIAM T. HAMLIN and CHARLES JOHANN, citizens of the United States of America, residing at Chicago, in the county of Cook and State of Illinois, have invented and produced a new and original Design for Broom and Brush Holders, of which the following is a specification, reference being had to the accompanying drawings, forming part thereof, in which—

Figure 1 is a front elevation of said holder. Fig. 2 is a side elevation of the holder, and Fig. 3 is a top plan view of the same.

As shown in the drawings, our design for a broom and brush holder is formed by bending a single piece of wire at the points and in the manner as follows: The wire is bent at the center to form the loop A and then bent outwardly at right angles to form the arms B, at the outer ends of which the wire is bent to

form the coils C and then bent inwardly to form the arms D, which are parallel to the arms B and partially overlap each other. From each of the arms D the wire is bent to form corresponding S-shaped holding-arms 25 E, at the extreme outer ends of which are formed small eyes e.

Having thus described our invention, what we claim as new, and desire to obtain by Letters Patent, is—

The design for a broom and brush holder substantially as herein shown and described.

In testimony whereof we affix our signatures in the presence of two witnesses.

WILLIAM T. HAMLIN.
CHARLES JOHANN.

Attest:

LOUIS CHASE,
J. BUEHLER.
